UNITED STATES PATENT OFFICE.

STEPHEN O. BUMGARNER, OF GIVEN, OHIO.

ELEVATOR FOR SILOS.

1,240,935.

Specification of Letters Patent. Patented Sept. 25, 1917.

Application filed March 10, 1916. Serial No. 83,340.

To all whom it may concern:

Be it known that I, STEPHEN O. BUMGARNER, a citizen of the United States, residing at Given, in the county of Pike and State of Ohio, have invented certain new and useful Improvements in Elevators for Silos; and I do hereby declare the following to be a full, clear, and exact description of the invention, such as will enable others skilled in the art 10 to which it appertains to make and use the same.

The object of this invention is to provide a novel type of elevator for association with a silo chute, which will admit of a person being carried to any point desired throughout 15 the height of the interior of the silo chute.

Another object of the invention is to provide a novel type of locking means for holding the elevator, when stopped, at any point 20 throughout the height of the silo and for automatically locking the elevator when moved to its maximum lowered position and when the operator steps from the platform of the elevator carriage.

Other objects will appear and be better understood from that embodiment of my invention of which the following is a specification, reference being had to the accompanying drawings forming a part thereof 25 in which:

Figure 1 is a front elevation of a silo showing the chute thereof in section and showing the improved elevator mounted within the chute.

Fig. 2 is a horizontal section taken on the line 2—2 of Fig. 1.

Fig. 3 is a section taken on the line 3—3 of Fig. 1 and looking in the direction of the arrows, and

Fig. 4 is a vertical front elevation of the elevator carriage.

Fig. 5 is a sectional detail view, taken through the upper end of one of the side walls of the chute.

Referring to the drawings more in detail, the letter A designates a silo of ordinary construction, and B one of the door openings therein, and C a chute located opposite the door openings.

Positioned within the chute C, is a pair of guides designated, respectively, by numerals 1 and 2, which have their upper ends secured to a transverse bar 3 which extends transversely of the chute C at the upper end

thereof and the lower ends of the guides 1 and 2 have connection with the floor of the chute.

Mounted for travel on the guides 1 and 2, is an elevator carriage 4. The carriage 4 consists of a vertically disposed body 5 having its forward side provided with pairs of rollers 6 which engage the guides 1 and 2 so as to minimize the frictional engagement between the guides 1 and 2 and the elevator carriage. The vertical body 5 of the carriage has its lower end provided with a platform 7, said platform being provided adjacent its opposite end with passages 8 for the passage of the guides 1 and 2. A cable 9 is located within the chute C and has its upper end passing over a sheave 10 which is rotatable through an opening 11 at the upper end of one side of the chute, and keyed to a shaft which is journaled in bearings of the upper end of the side of a chute 75 and the said cable 9 having the upper terminal thereof provided with a weight 12, which is located exteriorly of the chute C and the lower end of the cable 9 has connection with the ring 13 to which is secured 80 the upper ends of a pair of downwardly diverging chains 14, the lower ends of the chains having connection with a pair of pivoted levers 15, carried by the vertical portion 5 of the carriage. The weight 12 causes 85 the cable 9 to hold the levers 15 in positions shown in Fig. 4 and against the tension of springs 16, so that the outer ends of the levers 15 which are serrated as illustrated at 17 will be held out of engagement 90 with the guides 1 and 2. If the cable 9 should happen to break during the travel of the carriage, the springs 16 will pull downwardly on the inner ends of the levers 15 and cause the outer ends thereof to engage 95 the adjacent guides 1 and 2 and force the same against a pair of blocks 18, carried by the vertical portion 5 of the carriage, resulting in the gripping of the guides between the blocks and the levers and hold the carriage against movement.

The weight of the member 12 is sufficient to overcome the combined weight of the carriage 4 and the operator, so that the operator and carriage can be elevated to the top 105 of the silo or to any point within the silo, desired. However, when a sufficient amount of ensilage is placed on the carriage so that

the weight of the member 12 will be overcome, the carriage will descend to the bottom of the chute C.

As means for stopping the carriage at 5 different points throughout the chute C, stopping mechanism, designated as an entirety, by the numeral 19 is provided. This mechanism consists of a vertical reciprocating shaft 20 which is normally held in raised 10 position by means of a spring 21, and a pair of downwardly diverging links 22, the upper ends of which have connection with a foot pedal 23 carried by the upper end of the shaft 20 and the lower ends of the link are 15 connected to the inner ends of levers 24, the outer ends of the levers 24 being serrated, as shown at 25, and which outer ends normally engage and press the guides 1 and 2 against the adjacent blocks 26 for normally 20 holding the carriage against movement. When the operator depresses the shaft 20 the inner ends of the lever 24 will be moved downwardly and cause the outer ends thereof to be moved out of engagement with the 25 guides 1 and 2 and permit the travel of the carriage 4. When it is desired to stop the carriage at any point throughout the height of the chute, the shaft 20 is released resulting in the outer ends of the lever 24 pressing 30 the guides against the blocks 26 so as to stop the travel of the carriage. The carriage will also be locked against movement when the same is in lowered position as illustrated in Fig. 3 of the drawings, and when the 35 operator steps from the platform 8 of the carriage.

A chain 27 has one end secured to the axle or shaft for the sheave 10 and has its opposite end connected to the upper end of a vertically disposed spring 28, the lower end of 40 the spring having connection with the lower wall of the opening 11. During upward

travel of the elevator carriage 4 and the descent of the weight 12, the chain 27 will be wound around the shaft and effect an 45 expansion of the spring 28 so that when the elevator carriage reaches the maximum upward point in its travel, the tension under which the spring is placed and the weight of the carriage and the operator will 50 counterbalance the combined weight of the element 12 and that portion of the cable 9 which will be located at the outer side of the chute so that when ensilage is placed upon the carriage the latter will be caused 55 to descend.

Having thus described my invention what I claim as new is:

An elevator carriage for a silo chute including a horizontal portion having elevator 60 guide passages therein, a vertically disposed portion having connection with the horizontal portion at one edge thereof, elevator guide-engaging rollers carried by the vertically disposed portion of the carriage, a 65 pair of spaced blocks mounted adjacent the lower end of the vertically disposed portion, the said blocks being located, respectively, adjacent the vertical edges of the vertically disposed portion, and manually controlled 70 pivoted elevator guide-engaging elements mounted on the vertical portion of the carriage and located at the lower end thereof and disposed opposite the blocks at the lower end of the vertical portion and normally 75 lying in elevator guide-engaging position, for the purpose specified.

In testimony whereof I affix my signature in presence of two witnesses.

STEPHEN O. BUMGARNER.

Witnesses:

Mrs. J. LEE TORY,
IDA BRAMMER.
